(57) **CLAIM**

The ornamental design for a handbag, as shown and described.

DESCRIPTION

FIG. 1 is a left, front, perspective view of a handbag of my present invention.

FIG. 2 is a top plan view of FIG. 1 shown in an alternate, open position.

FIG. 3 is a bottom plan view thereof.

FIG. 4 is a left side elevation view thereof.

FIG. 5 is a right side elevation view thereof.

FIG. 6 is a front elevation view thereof; and,

FIG. 7 is a rear elevation view thereof.

The dash-dot-dash claim boundary lines in the interior demarcate the boundary beyond which no claim is made. The dash-dot lines shown beyond the claim boundary indicate portions of the article to which no claim is made. The chain-link type broken lines shown crossing the claimed surfaces depict claimed stitching.
